UNITED STATES PATENT OFFICE.

MILO ELSON, OF TODDVILLE, IOWA.

WAGON-END-GATE SEAT.

Application filed April 1, 1926. Serial No. 99,043.

This invention relates to wagon-box end-gates, and the object of the invention is to provide the side-boards of a wagon-box with strong and durable metal seats for the ends 5 of the end-gate, such seats being adapted to hold the end-gates securely in position, strengthen the side-boards, and hold them rigidly erect when the end-gate is removed.

The invention will clearly appear from 10 the description and claim following, reference being had to the accompanying drawing, in which:—

Fig. 1 is an elevation in perspective, showing 15 the device as attached to the wagon-box and in operative position. Fig. 2 is an elevation of the same as seen directly from the rear, the part being broken away to show the inner construction. Fig. 3 shows a section 20 of the same as seen from above the section line 3—3 of Fig. 2.

The device is designed to take the place 25 of the pair of upright wooden cleats commonly attached to wagon-box side-boards to retain the end-gate. These are very often the first part of a wagon to give out, by splitting, breaking or rotting away. The improved metal seat is easily attached in place of old wooden cleats, and if protected 30 by paint is practically indestructible.

A sheet of soft sheet steel of a length 35 suited to the depth of the wagon-box is crimped endwise to form a pair of folded longitudinal ribs 5, spaced apart at 6 to admit the end of the end-gate 7 (Fig. 3). Lateral flanges 8 are pierced for rivets 9, by which it is secured to the side-board 10. A hole 11 admits the tie-rod 12 by which the side-boards are clamped securely in place 40 against the ends of the end-gate. Near the lower end, one of the ribs has a counter depression 13, and is pierced to admit the hook-bolt 14 of a hook-bolt 14, which in hold-

ing position passes through the wagon-bed 15 and cross-cleat 16, and is drawn securely 45 in place by a nut and washer 17. A cotter-pin 18 holds the hook against displacement. To give increased stability to the structure, the fastening bolt is passed through a foot-plate 19, which has an upturned flange 20 to engage the outer side of the side-board 50 near the lower edge. The plate forms a small, but stable base for the lower end of the seat and edge of the board, and tends to hold the latter firmly in an upright position 55 at all times.

It will be noted that the folded ribs are braced at 5^a by the diagonal disposition of the outer portions of the ribs in cross section, thus giving the ribs great strength to resist lateral pressure thereon. Partly as 60 a neat finish for the upper end, but mainly to exclude moisture, a part of each rib at 5^b is folded over to close the opening at the top.

It will be evident that the seat may be applied to the extra side-boards that are placed on top to increase the depth of the wagon body. In this case the fastening bolt and its special connection with the seat is dispensed with, as the upper side-board is held 70 in position otherwise on top of the lower side-board.

Having thus described my invention, I claim:

A wagon-box end-gate seat formed of 75 sheet metal folded endwise, with outer, lateral flanges, the folds forming end-gate-retaining ribs braced outwardly and closed at the upper ends, one of the ribs having a re-entrant depression to partially admit a bolt, 80 and pierced for the hook of said bolt, and a hook-bolt secured therein.

In testimony whereof I affix my signature.
MILO ELSON.
